UNITED STATES PATENT OFFICE.

EDWIN X. SCHMIDT AND ULRIC O. HUTTON, OF MILWAUKEE, WISCONSIN, ASSIGNEES
TO THE CUTLER-HAMMER MFG. CO., OF MILWAUKEE, WISCONSIN, A CORPORA-
TION OF WISCONSIN.

METHOD OF AND APPARATUS FOR ASCERTAINING THE PROPORTION OF A CONSTITU- ENT IN A FLUID.

Application filed January 30, 1924. Serial No. 689,455.

To all whom it may concern:

Be it known that we, EDWIN X. SCHMIDT and ULRIC O. HUTTON, citizens of the United States, residing at Milwaukee, in the county of Milwaukee and State of Wisconsin, have invented new and useful Improvements in a Method of and Apparatus for Ascertaining the Proportion of a Constituent in a Fluid, of which the following is a full, clear, concise, and exact description, reference being had to the accompanying drawing, forming a part of this specification.

This invention relates to a method of and apparatus for ascertaining the proportion of a constituent in a fluid.

More particularly, the invention relates to a method of and apparatus for ascertaining the proportion of a constituent in a fluid by electrical means.

One object of our invention is to provide a device of the above character of rugged, simple and compact construction.

Another object is to provide a device for ascertaining the proportion of a constituent of a compound fluid by electrical means in an improved manner.

Another object is to provide a device for ascertaining the proportion of a fluid constituent, utilizing the differential of thermic expansion of elements subjected respectively to influence of the test fluid and another medium.

Various other objects and advantages of the invention will hereinafter appear.

Referring to the accompanying drawings:

Figure 1 is a vertical sectional view of a device constructed in accordance with our invention, and

Fig. 2 is a front elevation of the same, portions of the device being shown in section.

Referring to the drawing the numerals 1 and 2 indicate a pair of chambers, said chambers being preferably of tubular shape and being substantially closed at the upper ends thereof by a cap member 3, which is provided with a portion 4 forming a housing for a roller 5, said roller having extensions or projections 6 and 7 fitted into the walls of the housing 4 to form a rotatable support for said roller.

Slidable in the lower ends of the tubes 1 and 2 are pistons 8 and 9, respectively, and

extending through said pistons and rigidly connected therewith are insulating posts 10 and 11. The lower ends of said posts 10 and 11 are preferably provided with screw threads to receive nuts 13 and 14, 15 and 16, an insulating block 12 being adapted to be clamped between the upper pair of nuts 13 and 15 and the lower pair of nuts 14 and 16 to rigidly connect said block and the insulating posts 10 and 11. Surrounding tubes 1 and 2 and rigidly secured thereto in any suitable manner are spaced blocks 17 and 18, said blocks being provided with vertical openings to receive a pair of guide rods 19 and 20, as illustrated in Fig. 2. The lower ends of said rods are screw threaded to receive nuts 21 and 22 adapted to support the insulating block 12 which is clamped thereagainst by means of nuts 23 and 24. Interposed between the blocks 12 and 17 and surrounding the rods 19 and 20 are springs 25 and 26 tending to separate said blocks. The guide rods 19 and 20 insure horizontal positioning of the insulating block 12 at all times. A conducting wire 27 is attached to the insulating post 10, said wire extending upwardly through the tube 1 to the roller 5 around which it is coiled a number of times and thence extends downwardly through the tube 2 and is attached to the insulating post 11. Said wire 27 is connected at the insulating posts 10 and 11 with a suitable source of electric current for heating said wire, as indicated by lines L' and L". Suitable means, such as a rheostat 28, may be provided to regulate the supply of energy to said wire.

Secured to the extension 6 of the roller 5 and adapted to turn therewith is an arm 29 having a gear segment 30 at the lower end thereof adapted for engagement with a spur gear 31 attached to a shaft 32 rotatably supported by the cap 3. The outer end of said shaft is provided with an indicating hand 33 adapted to rotate therewith and arranged to cooperate with an indicating dial 34.

Tube 1 is preferably provided with openings 35 and 36 which permit entrance and exit of a standard fluid medium such, for example, as atmospheric air, whereas tube 2 is provided with nipples 37 and 38 having openings 39 and 40 therein which permit entrance and exit of the test fluid. The open-

ings 42 and 43 in cap 3 above tubes 1 and 2 may be of a size just large enough to permit passage of wire 27, or said openings may be provided with disks 44 and 45 of insulation 5 or the like, as shown.

The operation of the device is as follows: Assuming for purposes of illustration that both portions of the wire 27 in the respective tubes 1 and 2 are surrounded by a medium such as air. Upon heating the wire 27 the portions thereof in said tubes will expand an equal amount, thus permitting the springs 25 and 26 to move the block 12 and attached insulating posts downwardly an equal amount without affecting that portion of the wire which is coiled around the roller 5. However, if air is permitted to pass through tube 1, and a continuous stream of flue gases, for instance, is permitted to enter the opening 39 at the lower end of tube 2 and escape through opening 40 at the upper end thereof, there will be a difference in the rate of expansion of the two portions of the wire due to the presence of carbon dioxid in the last mentioned tube. This is due to the fact that carbon dioxid has about forty per cent less heat conductivity than air whereas the other main constituents of flue gases all have practically the same heat conductivity as air. Thus the portion of wire in tube 2 will become hotter than the wire in tube 1 in direct proportion to the percentage of carbon dioxid contained in the flue gases, and will accordingly expand a proportionately greater amount than the portion of wire in tube 1. The resulting difference in length of the two portions of wire 27 will be taken up by downward movement of the block 12 and the attached parts under the action of springs 25 and 26 to bring both portions of the wire to the same degree of tension. In other words, the difference in length of the two portions of the wire under such conditions will be equally divided between the same, one half of such additional length being wound upon the roller 5 above the tube 2 and a corresponding portion unwound from said roller above the tube 1. This winding and unwinding movement of the wire will cause a corresponding movement of the roller 5 which is communicated through the arm 29 and through gearing 30 and 31 to the indicating hand 33, to indicate the percentage of carbon dioxid in said flue gases. If desired the wire 27 may be rigidly fastened to the roller 5 as indicated at 41, but ordinarily there is sufficient friction between the coils of the wire and the roller 5 to obviate the necessity for such fastening means.

Inasmuch as the flue gases being treated are usually saturated with water vapor, to compensate for possible errors the air or other standard medium in tube 1 may also be saturated with water vapor in any well

known manner, or both the flue gases and air may be dried before entering the respective tubes. The flue gases pass through tube 2 at substantially atmospheric pressure, which pressure corresponds with that in tube 1, as will be obvious. Any suitable means may also be provided for introducing the flue gases and air into the respective tubes at substantially the same temperature.

What we claim as new and desire to secure by Letters Patent is:

1. The method of ascertaining the proportion of a constituent in a fluid, which comprises simultaneously subjecting dimensionally proportioned portions of a thermally expandable medium to influence respectively of the test fluid and of a standard medium, the temperature of said first mentioned medium being maintained different from that of said test fluid, and utilizing the differential of the resultant changes in dimension of such portions of said first mentioned medium in indicating the proportion of such constituent in the test fluid.

2. The method of ascertaining the proportion of a constituent in a fluid, which comprises subjecting a portion of a heated element to influence of said fluid and subjecting another portion of said element to influence of a standard fluid, and utilizing the difference in expansion of said portions of such element to indicate the proportion of such constituent.

3. The method of ascertaining the proportion of a constituent in a fluid, which comprises simultaneously subjecting different portions of a heated element to contact with said fluid and another medium respectively and utilizing the differential of expansion of said portions of the element under such conditions to indicate the proportion in a constituent of said fluid.

4. The method of ascertaining the proportion of a constituent in a fluid, which comprises subjecting portions of a heated wire in separate chambers to contact with a fluid and another medium respectively while maintaining said portions of the wire at equal degrees of tension and utilizing the movement of said wire due to the differential of expansion of said portions thereof to indicate the proportion of a constituent in said fluid.

5. The method of continuously ascertaining the proportion of carbon dioxid in flue gases, which comprises simultaneously subjecting different portions of a heated element to contact with said flue gases and another medium respectively, and utilizing the differential of expansion of said portions of the element to indicate the proportion of carbon dioxid in said flue gases.

6. The method of ascertaining in a continuous manner the proportion of carbon dioxid in flue gases, which comprises sub-

jecting a portion of an electrically heated wire to contact with a flow of said flue gases and simultaneously subjecting a proportioned dimension of said wire to contact with another medium, and utilizing the differential of expansion of said portions of the wire to indicate the proportion of carbon dioxide in said flue gases.

7. The method of ascertaining in a continuous manner the proportion of carbon dioxide in flue gases, which comprises subjecting a portion of an electrically heated wire to contact with a flow of said flue gases and simultaneously subjecting another equal portion of said wire to contact with an equal volume of another medium having substantially the same degree of heat conductivity as the other constituents of the flue gases, and utilizing the difference in expansion of said portions of the wire under such conditions as a measure of the proportion of carbon dioxide in said flue gases.

8. The method of continuously ascertaining the proportion of a constituent in a fluid, which comprises simultaneously subjecting different portions of an electrically heated wire to contact with said fluid and another medium respectively under like conditions of temperature pressure and saturation, and utilizing the difference in expansion of said portions of the wire as a measure of the proportion of said constituent.

9. The method of ascertaining the proportion of a fluid constituent, utilizing variations in thermal conductivity of the fluid with variations in proportion of such constituent thereof, which comprises subjecting an element to thermic influence continuously proportional to the value of the thermal conductivity of such fluid and comparing continuously the value of a resultant mechanical effect upon said element of the variations in such influence with the corresponding effect upon an element subjected to standardized conditions of thermic influence.

10. The method of continuously ascertaining the proportional value of a constituent in a fluid, which comprises simultaneously subjecting substantially equal lengths of heated wire to contact with said fluid and a standard medium respectively, and utilizing the difference of expansion of said lengths of wire under such conditions as a measure of the proportional value of said constituent.

11. Apparatus for determining the proportional value of a fluid constituent, comprising a pair of elements having substantially equal coefficients of expansion, means for subjecting said elements to a common

source of heat while surrounded by said fluid and a standard medium respectively, and means for measuring the difference of expansion of said elements under such conditions to indicate the proportional value of said constituent.

12. Apparatus for ascertaining the proportion of carbon dioxide in flue gases, comprising a pair of conduits for the flue gases and a fluid having a standard value of heat conductivity respectively, a resistance element in each of said conduits, a common source of electric current therefor, and means for measuring the difference in expansion of said elements to indicate the proportion of said carbon dioxide.

13. A device of the character described, comprising an element having equal portions thereof subjected to a common source of heat, and means interposed between said heated portions to indicate the differential of expansion thereof when simultaneously exposed to a standard medium and a test fluid respectively.

14. A device for ascertaining the proportion of a constituent in a fluid comprising, in combination, a heated wire, means for subjecting different portions of said wire to contact with said fluid and another medium respectively, and means for utilizing the differential of expansion of said portions of the wire to indicate the proportion of a constituent in said fluid.

15. A device for ascertaining the proportion of a constituent in a fluid, comprising, in combination, an electrically heated wire, chambers enclosing substantially equal portions of said wire, means permitting flow of said fluid and a standard medium through the respective chambers in contact with said portions of the wire, and means for measuring the difference in expansion of said portions of the wire to indicate the proportion of said constituent.

16. A device for ascertaining the proportion of carbon dioxide in flue gases, comprising a pair of expansible heated elements, means for subjecting one of said elements to contact with a flow of said flue gases and simultaneously subjecting the other element to contact with a medium having substantially the same value of heat conductivity as the other constituents of said flue gases, and means for measuring the difference in expansion of said elements to indicate the proportion of said carbon dioxide.

In witness whereof, we have hereunto subscribed our names.

EDWIN X. SCHMIDT.
ULRIC O. HUTTON.
